UNITED STATES PATENT OFFICE.

WILLIAM B. ANDERSON, OF CHICAGO, ILLINOIS, ASSIGNOR TO HAGGARD AND MARCUSSON COMPANY, OF CHICAGO, ILLINOIS, A CORPORATION OF ILLINOIS.

CORNER-BRACKET FOR BED-BOTTOMS.

1,266,755.

Specification of Letters Patent. Patented May 21, 1918.

Application filed January 20, 1917. Serial No. 143,439.

To all whom it may concern:

Be it known that I, WILLIAM B. ANDERSON, a citizen of the United States, residing at Chicago, in the county of Cook and State 5 of Illinois, have invented certain new and useful Improvements in Corner-Brackets for Bed-Bottoms, of which the following is a specification.

My invention relates to corner brackets 10 for bed bottoms whereby to connect the side rails of the frame to the end rails of such structures.

One of the objects of my invention is to generally improve devices of this character 15 whereby to reduce the cost of production; to increase the strength; improve the appearance, and to produce convenient means whereby the height of the end rails, above the side rails, of the frame, may conveniently be varied by changing the length of 20 the tubes employed to join the two members of the bracket.

Other and further objects of my invention will become readily apparent, to persons skilled in the art, from a consideration 25 of the following description when taken in conjunction with the drawings, wherein:—

Figure 1 is a plan view of the corner bracket, showing fragments of the side and 30 end rails of the frame connected thereto and a piece of the spring fabric in place.

Fig. 2 is an end view of the bracket.

Fig. 3 is a side elevation of the bracket.

In all the views the same reference characters are employed to indicate similar parts.

The bracket consists of two members and interconnecting parts or tubes.

The top member 5 is, preferably, a casting 40 for connection with an end rail, which may take the form of an angle-iron bar, as shown, and the member 7, which is also preferably a separate casting, for connection with the side rail 8, which is shown to 45 be of tubular form and, preferably, elliptical in cross section, with its greatest diameter in a vertical plane. This shape improves the appearance of the structure and distributes the metal to the best advantage to resist the greatest strain which is exerted in 50 vertical planes.

The member 5 is provided with an angular part 9 having undercut angularly-disposed ribs, 10 and 11, to overlie the end of 55 the angularly-disposed flanges, or members,

of the end rail, to provide a smooth finish where the joint is made. Extending laterally and inwardly from the member 5, and of the end rail 6, to which it is connected, is a plate 12, which underlies the horizontally disposed flange 13 of the angle bar and is connected to the vertical flange 14, as by rivets 15, or the like. Projecting at an angle to the horizontal plane and constituting an integral part of the plate 12, is a 60 socket 16 to receive the member-connecting tube 17. The bracket 7 is provided with a socket 18, which is projected at an angle from the horizontal, substantially equal to that of the coöperating socket in the member 5, to receive the other end of the connecting tube 17. Another socket 19 projects horizontally from the member 7 to receive the preferably tubular side rail 8.

Spaced apart from the socket 16 of the 75 member 5, and projecting at substantially the same angle, is another socket 20, for a connecting tube 21. A corresponding socket 23, projects upwardly from the member 7 for accommodation of the other end of the 80 connecting tube 21. The sockets 19 and 23 are joined together by a webbed plate 24, which rests on the bed frame.

The length of the connecting tubes 17 and 21, determines the height that the end rail 6 85 is to be located above the side rail 8, so that to vary the height, or distance of separation between these rail members, it is only necessary to change the length of the connecting tubes 17 and 21. The outer end of the 90 bracket member 5 is provided with an in-turned lip 25 to which the selvage border 26 of the spring fabric may be connected, as by rivets 27, or the like. The spring fabric 28 is connected at intervals to the end rails, as 95 by helical springs 29, as usual in such structures.

By constructing my corner bracket, in the manner described, wherein an end rail member may be joined to a side rail member by tubes of varying length, bed bottoms, in which the separation between the side and end rails differ in extent, and of which there are a large variety, may be produced without any change in the character of the 100 bracket members except in the length of the tubes which connect these members together, thus saving the cost and inconvenience of carrying in stock special corner brackets for each type of bed bottoms.

Having described my invention, what I claim is:—

1. In a bed bottom frame the combination with a side rail and an end rail, of a corner bracket, for joining the rails together, comprising a top member having a part for connection with the end rail, and an outwardly projecting part, to which to connect the marginal border of the spring fabric to be connected to the frame, and a part for connection with an end rail thereof; a bottom bracket member, having a part for connection with the side rail and a part projecting outwardly into substantially the vertical plane with the border-connecting part of the upper member, and means, in the vertical plane of the side rail and other means in the vertical plane of the border connecting member, to connect the two bracket members together.
2. A corner bracket for a bed bottom frame comprising two separable members, each having a part for connecting the side and end rails of a frame and an outwardly

projecting part, one for the selvage border 25 of the wire fabric and the other for support upon the side rail of a bed and two substantially parallel members for connecting said bracket members together.

3. In combination with a bed frame having an angular end rail and a tubular side rail, of a two part bracket, for joining the rails one above the other, one part having a tubular socket for engagement with the side rail and an angularly disposed socket to receive a connecting tube, the other part having a flange to overlie the abutting end of the angular end rail and a socket angularly disposed to receive the connecting tube whereby to connect the rails together with 40 the end rail above the side rail.

In testimony whereof I hereunto set my hand in the presence of two subscribing witnesses.

WILLIAM B. ANDERSON.
